UNITED STATES PATENT OFFICE

PER GUNNAR PALMGREN, OF GOTTERBORG, SWEDEN, ASSIGNOR TO AKTIEBOLAGET SVENSKA KULLAGERFABRIKEN, OF GOTTERBORG, SWEDEN, A CORPORATION OF SWEDEN

DEVICE FOR HANDLING BAR MATERIAL IN ROLLING MILLS

Application filed November 26, 1929, Serial No. 409,787, and in Sweden December 1, 1928.

When rolling bar material, such as steel bars or the like, it is generally necessary to have a number of workmen on each side of the mill to grip and support the bar by means of 5 tongs and move it from one pass in the rolls to another. For heavy dimensions it is also usual to employ lifting tables, tilting tables, etc., in which case, however, it is also frequently necessary to have a certain number 10 of workmen to assist in handling the bar. When rolling round steel bars without guides, the workmen in addition to the ordinary work are also required to hold and steady the bar while it is being rolled in order to 15 prevent it from twisting in the pass. This method of rolling requires, as a rule, more workmen than other rolling methods. Since the workmen must go back and forth with each bar, the work is very tiresome and the 20 length of the bars must be limited, and the speed of the mill must be kept low, which, of course, will tend to lower the output.

The present invention has for its object to 25 simplify and cheapen the rolling of such material by either reducing as much as possible the necessary number of workmen or else making possible the rolling of appreciably greater lengths at a considerably higher speed than what has heretofore been possi- 30 ble.

The essential feature of the invention consists in the provision of a movable gripping and supporting member for holding the bar material cooperating with mechanical motion transmitting devices for moving the bar material from one pass in the rolls to another. 35 These motion transmitting members can here be made and arranged in such a manner that it is possible to either move the bar material in its longitudinal direction or turn it about an axis parallel with this direction. The motion transmitting members can also be so made and arranged that the bar material can be turned about an axis at right angles to the 40 direction mentioned above so that the end of the bar nearest the rolling mill can either be raised or lowered and brought in a position opposite a roll pass either above or below. The motion transmitting members can, fur- 45 thermore, be arranged for moving the bar

material in a direction parallel to itself. With the motion transmitting members which are intended to move the bar material in a longitudinal direction it is also possible to combine devices for opening or closing the 55 gripping members.

By means of such an arrangement it will thus be possible to grip, turn, and raise or move and support the bar material mechanically without the use of manual power. For 60 effecting the various motions it is suitable to arrange electric motors that can be operated independently of each other from a common operating station, which can be attended by one man.

The device being rotatable about a shaft 65 parallel with the longitudinal direction of the bar material it also possesses the combined features of the ordinary lifting table and tilting table, and the cost will not be higher 70 than for a tilting table, lifting table, etc. with appurtenant live roller gear beds and the like. As above mentioned, it also has the additional advantage that the bar material will be handled purely mechanically, and that the 75 number of workmen can be appreciably reduced. The device will be used to greatest advantage in the rolling of round material without guides inasmuch as the reduction of the number of workmen will be greater while 80 at the same time the production will be increased by the possibility of rolling greater lengths and increasing the speed.

The accompanying drawings show one 85 form of a device according to the invention.

Fig. 1 is a section along the line 1-1 of Fig. 2.

Fig. 2 is a top view.

Fig. 3 is a section along the line 3-3 of Fig. 1.

Fig. 4 is a section along the line 4-4 of Fig. 1, showing a detail in the mechanism for closing the gripping arrangement.

Fig. 5 is a section along the line 5-5 of Fig. 1, showing the shape of the running 95 groove, and

Fig. 6 is a view looking at the right hand end of Figs. 1 and 2.

In Fig. 1 the rolling mill is shown at 1 as a three-high mill with rolls 2, 3, and 4. The 10

figure shows the arrangement ready to receive a bar after passing between the rolls 3 and 4. For this purpose it is provided with a pair of movable jaws 5 and 6 mounted on a carriage 7. The carriage can be moved on rails 12 with the aid of the motor 8 and a wire 9 running on sheaves 10 and 11. The motion of the motor is transmitted to the wire by means of the pinion 13 fixed to the 10 motor shaft and the bevel gear 14. The bevel gear 14 and the sheave 11 are mounted on a common shaft 15. The wire is at both ends fastened to the carriage 7 thus enabling the carriage to be moved in both directions.

15 When the front end of the bar has passed through the mill, it enters the gap between the jaws 5 and 6 and continues into a guide 16 provided for its guidance and support. The guide 16 is fixed to and movable with the 20 carriage 7. When the bar has continued a suitable distance, the carriage is set in motion by means of the motor 8. As the carriage moves to the right, a wheel 17 movably mounted in a vertical direction on the carriage and acted upon by a strong spring 18 will follow the surface of a cam 19 which is given such a shape that the wheel will move upwards. The links 20 and 21 cooperating with the jaws 5 and 6 are thus raised. The 25 jaw 5 turns about a stud 22 and is at one of its ends connected to the link 20. The jaw 6, on the other hand, turns about a stud 23 and bears with its other end against a lever 24 which rotates about a stud 25 and is at one 30 of its ends connected to the link 21. When the links 20 and 21 are raised, the jaws 5 and 6 will then approach each other and grip the bar. In order to support the bar when the carriage is moved to the right, a support 54 is 35 fixed to the rails 12.

It is now possible to turn the bar 90° about the axis of bearings 26 and 27 and bring it between the rolls 2 and 3. If desired, it is, however, possible to turn the bar 45° or any other 45 desired angle. This is made possible through the fact that the entire upper part with the carriage 7, rails 12, support 54, and the motor 8 can turn in the bearings 26 and 27. The turning movement is imparted by the motor 50 28 which, by means of a universal joint 29, drives a worm 31 in mesh with the worm wheel 30 in the housing 32. The motion can, of course, also be imparted through any other suitable connection between the motor and the 55 rotatable rail system. The distance between the jaws and the axis of rotation can be chosen so that after the turning movement is completed the bar will be situated immediately in front of a pass between the rolls 2 and 3.

60 The arrangement of the carriage wheels and the rails for holding the carriage on the rails during the rotation will be seen from Fig. 3. The rails 12 are four in number and placed crosswise. The carriage is provided with 65 wheels 42, four at each end. The wheels are

arranged in such a manner that the carriage in all positions is supported by two wheels at each end. In order to make it possible for the entire machinery to be moved parallel to itself it is mounted on wheels 33 which run on rails 34. The motion may be obtained from a motor 35 mounted on a pair of longitudinal girders 36. By means of the pinion 37 and the gear 38 the motor drives a shaft 39 which at each end is fitted with a pinion 40 in mesh with the gear 41 fixed to the wheels 33.

70 In cases where the bar is not to be turned or turned in any other angle than 90°, the arrangement of the device is designed for a tilting motion. For tilting it is provided with a fourth motor 43 mounted on a bracket 44 at the end nearest to the rolling mill. The motor 43 is connected to the shaft 45 through the worm gear 46, the pinion 47 and the gear 48. When the motor is set in motion, the shaft 45 is turned, bringing with it the levers 49 attached thereto, these levers being at their one end connected to a link 50 connected by means of an articulated joint to the bearing housing 26 at 51. The rails 12 will thus be raised by the motor at the end nearest the mill turning on bearings 52 mounted on the bearing housing 27 at the opposite end of the rails. With a view to facilitating the tilting, the levers 49 are at their other ends provided with counterweights 53.

Claims:

Having described my invention, I claim and desire to secure by Letters Patent:

1. A device for handling bar material in rolling mills characterized by an axially movable gripping member cooperating with mechanical motion transmitting means for moving the bar material from one pass in the rolls to another, and means actuated by the axial movement of the gripping member to close the said gripping member on the work.

2. A device as claimed in claim 1 characterized by the arrangement of the mechanical motion transmitting means in which the movement of the bar takes place about an axis parallel to that of the bar, and located at such a distance from the axis of the bar that upon the completion of the turning movement the bar will be situated immediately in front of a pass in the rolls.

3. A device as claimed in claim 1 characterized by the arrangement of the mechanical motion transmitting means in which the movement of the bar takes place about an axis perpendicular to that of the bar in such a manner that the end of the bar nearest the mill is swung in a vertical direction from one pass to another.

4. A device for handling bar material in rolling mills characterized by an axially movable gripping member cooperating with mechanical motion transmitting means for moving the bar material from one pass in the rolls to another about an axis parallel to that of

the bar and in a direction longitudinally thereof, mechanism for opening and closing the gripping member and means for operating the same upon the longitudinal movement thereof.

5. A device for handling bar material in rolling mills characterized by an axially movable gripping member cooperating with mechanical motion transmitting means for moving the bar material from one pass in the rolls to another about an axis parallel to that of the bar and in a direction longitudinally thereof, and a series of electric motors, each operated independently from a common operating station, for imparting motion to the various motion transmitting means.
10. 6. A device of the character specified, the combination with a carriage, of a series of rails upon which the carriage is adapted to be shifted, combination with a bar gripping device mounted upon the carriage, and means for rotating the system of rails about an axis parallel with their general direction of disposition, the organization being such that the carriage is supported by at least two rails in any position of the rail system.
